UNITED STATES PATENT OFFICE.

RICHARD W. JEFFERIS, OF CAMDEN, NEW JERSEY.

ATTACHING DEVICE FOR LOCKER-DOOR HINGES.

1,070,479.

Specification of Letters Patent. Patented Aug. 19, 1913.

Application filed June 19, 1912. Serial No. 704,477.

To all whom it may concern:

Be it known that I, RICHARD W. JEFFERIS, a citizen of the United States, residing at Camden, in the county of Camden and State 5 of New Jersey, have invented certain new and useful Improvements in Attaching Devices for Locker-Door Hinges, of which the following is a specification.

My invention relates to improvements in 10 attaching devices for locker door hinges, the object of the invention being to provide an improved construction of hinge and means securing the same to the locker, which permits the door to be quickly secured in place 15 when assembling the locker and insure a perfect fit of the door.

A further object is to provide a locker door hinge which may be quickly secured to a locker and readily removed therefrom and 20 which will securely hold the door with its hinge pins in proper alinement.

With these and other objects in view, the invention consists in certain novel features of construction and combinations and arrangements of parts as will be more fully 25 hereinafter described and pointed out in the claims.

In the accompanying drawings: Figure 1 is a view in front elevation showing a plurality of lockers with my improved hinge construction thereon. Fig. 2 is a fragmentary view in horizontal section on the line 2—2 of Fig. 1. Fig. 3 is a view in section on an enlarged scale on the line 3—3 of Fig. 35 2. Fig. 4 is a perspective view of my improved hinge, and Fig. 5 is a perspective view of the hinge holding key.

The lockers 1 are preferably arranged in series as shown in Figs. 1 and 2, and the upper 40 right channels 2 at the front are secured to partitions 3 in any approved manner. The particular construction of locker is not material to my invention, except that it is necessary to provide upright channels 2 or 45 other angle bars capable of supporting the doors 4 which are connected at one edge to the channels 2 by means of my improved hinges 5. Each door may have any number of hinges, two being illustrated, and each 50 hinge comprises two leaves 6 and 7 respectively, connected by a hinge pin 8. The leaf 6 is appreciably larger than leaf 7 and is secured to the inner face of door 4 by means of a rivet 9 or in any other improved manner. The door is so shaped that its main 55 portion lies between the channels 2 and only

its extreme edges are positioned against the channels.

The channel 2 at the hinge edge of the door, is provided with longitudinal slots 10 through which the hinge leaves 7 are projected. These leaves 7 have recesses 11 and 12 in their upper and lower edges respectively, the lower recess 12 adapted to receive the lower wall of slot 10 when the hinge is moved downwardly and prevent withdrawal of the hinge until it is elevated.

To lock the hinge leaves 7 in the channels, keys 13 are provided. Each key is composed of a strip of metal bent at two points at 70 right angles forming parallel ends 14 connected at their upper ends. These ends 14 have recesses 15 in their lower ends and one end 14 is preferably longer than the other. The longer end 14 is positioned against the inner face of channel 2, and straddles the leaf 7 engaging in the upper recess 11 while the shorter recessed end 14 straddles the upper edge of the leaf in rear of the recess 15.

It is to be noted that the metal bar forming the key 13 is of such a width that it snugly fits the channel 2, so that when forced into place as shown in Figs. 2 and 3, the hinge will be held against movement 80 and the door given a rigid hinge mounting.

Various slight changes might be made in the general form and arrangements of parts described without departing from my invention, and hence I do not limit myself to 85 the precise details set forth, but consider myself at liberty to make such changes and alterations as fairly fall within the spirit and scope of the appended claims.

Having thus described my invention, what I claim as new and desire to secure by Letters Patent is:

1. The combination with a support having a slot therein, of a hinge having one leaf removably projected through the slot 100 in the support, said hinge at its lower edge having a recess positioned over the lower wall of the slot, and a separable locking member having a recessed lower end to receive the hinge positioned against the hinge 105 and against the inner face of the support, whereby the hinge is secured to the support, substantially as described.

2. The combination with a support having a slot therein, of a hinge having recesses 110 in opposite edges, said hinge adapted to be positioned through the slot and its lower re-

cess receiving the lower wall of the slot, and a locking member independent of the support and the hinge and positioned against the inner face of the support and located in 5 the upper recess of the hinge, substantially as described.

3. The combination with a support having a slot therein, of a hinge having recesses in opposite edges, said hinge adapted to be 10 positioned through the slot and its lower recess receiving the lower wall of the slot, a locking member positioned against the inner face of the support and located in the upper recess of the hinge, said locking member 15 comprising a key having a recess therein, whereby the lower portion of the key straddles the hinge, substantially as described.

4. The combination with a support having a slot therein, of a hinge having recesses 20 in opposite edges, said hinge adapted to be positioned through the slot and its lower recess receiving the lower wall of the slot, and a locking member positioned against the inner face of the support and located in the 25 upper recess of the hinge, said locking member comprising a bar bent at two points at right angles forming parallel legs having recesses at their lower ends, one recessed end

engaging in the upper recess in the hinge, and the other recessed end engaging the upper edge of the hinge, substantially as described. 30

5. The combination with a support having a slot therein, of a hinge having recesses 35 in opposite edges, said hinge adapted to be positioned through the slot and its lower recess receiving the lower wall of the slot, and a locking member positioned against the inner face of the support and located in the upper recess of the hinge, said locking member 40 comprising a bar bent at two points at right angles forming parallel legs having recesses at their lower ends, one recessed end engaging in the upper recess in the hinge, and the other recessed end engaging the upper 45 edge of the hinge, said key of a width to snugly fit within the support, whereby lateral movement of the key is prevented, substantially as described.

In testimony whereof I have signed my 50 name to this specification in the presence of two subscribing witnesses.

RICHARD W. JEFFERIS.
